DESIGN FOR A BOTTLE

James S. Steelman, Millville, N. J., assignor to
Whitall Tatum Company, Millville, N. J., a
corporation of New Jersey

Application April 25, 1936, Serial No. 62,301

Term of patent 14 years

To all whom it may concern:

Be it known that I, James S. Steelman, a citizen of the United States, residing at Millville, Cumberland County, New Jersey, have invented a new, original, and ornamental Design for a Bottle, of which the following is a specification, reference being had to the accompanying drawing, forming part thereof.

Figure 1 is a front view;

Figure 2 is a rear view; and

Figure 3 is a bottom view of a bottle showing my new design.

The characteristic features of my design re-

side in the application of a sugar cane motif to a bottle in such manner that stalks of sugar cane extending upwardly from the base on opposite sides of the bottle are draped across adjacent the shoulder, thereby to outline plain surfaced portions on the body, together with wreath-like ruffs extending about the base and neck of the bottle.

I claim:

The ornamental design for a bottle as shown and described.

JAMES S. STEELMAN.
